(57) **CLAIM**

We claim the ornamental design for a model vehicle roof feature, as shown and described.

DESCRIPTION

FIG. 1 is an upper, left, front perspective view of a model vehicle roof feature;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an upper, left, front perspective environmental use view of the model vehicle roof feature.

In the drawings, the broken line showing of features of the model vehicle roof feature illustrate portions of the model vehicle roof feature that form no part of the claimed design; whereas, the broken line showing of the environmental use view depicts environmental subject matter and is provided for the purposes of illustrating environmental use structure and context and also forms no part of the claimed design.
